UNITED STATES PATENT OFFICE.

ADALBERT A. RUMREICH, OF PISEK, NORTH DAKOTA.

LIGNITE-GRAVE.

1,381,887.

Specification of Letters Patent. Patented June 14, 1921.

Application filed October 9, 1918. Serial No. 257,451.

To all whom it may concern:

Be it known that I, ADALBERT A. RUMREICH, a citizen of the United States, residing at Pisek, in the county of Walsh and 5 State of North Dakota, have invented new and useful Improvements in Lignite-Grates, of which the following is a specification.

This invention relates to the art of stoves and furnaces and relates specifically to an 10 improved construction of grate adapted for use in the consumption of lignite and the like.

The object of this invention is to provide a grate which is adapted for use in stoves 15 of various sizes and designs; which may be applied to the stoves without altering the construction thereof; which may be adjusted to accommodate the grate to stoves varying in size so that the grate may be pro- 20 portioned to the size and character of the stove for maintaining the desired amount of fuel in the firepot, which may be used in combination with the ordinary stove grate; and to provide a grate which is adjustable 25 for varying the amount of air which may be fed to the middle portion of the bulk of fuel supported on the grate.

The grate of this invention also embodies a construction wherein the grate may be 30 mounted in the firepot of a stove by the removal of the grate and shaker ring, or by the removal of the grate alone.

Heretofore lignite has been discarded on account of the necessity of providing separate stoves for its consumption, and it is 35 the design of this invention to provide a grate which may be used in the ordinary stove when lignite is to be burned, and which may be removed when ordinary coal 40 may be obtained. Thus shortage in the supply of coal may be offset by the consumption of the lignite. It is well known that lignite packs upon the grate and air has no access to the middle of the mass and 45 consequently upon shaking the grate a large amount of the unconsumed lignite falls into the ash pit and not only is lost but also unduly heats the ash pan and prevents the satisfactory handling of the ashes.

50 The above, and various other objects and advantages of this invention will be in part described in, and in part understood from, the following detailed description of the present preferred embodiment, the same being illustrated in the accompanying drawings, wherein:

Figure 1 is a vertical fragmentary section through the fire pot of a stove having a grate constructed according to the present invention mounted therein.

60

Fig. 2 is a detail top plan view of the centering device or holder.

65

Fig. 3 is a fragmentary, enlarged view in section of adjacent grate sections with an adjustable connection therebetween.

65

Fig. 4 is a top plan view of the same.

70

While the accompanying drawings illustrate the preferred embodiment of this invention, it is to be understood that the grate may be of any suitable size, shape, material and number of sections to meet practical demands of the user and the manufacturer.

Referring to the drawing wherein like parts are designated by similar numerals of reference throughout the several views, 12 75 designates the fire pot of a stove and 11 the inwardly extending lugs for supporting the usual grate 26, the latter having a suitable shaker handle 27 extending outwardly through the front of the fire pot 12.

80

The grate of this invention comprises a plurality of superposed grate sections 22, and a top grate section 20 spaced above the lower sections 22. Each section 22 is of

85

frusto-conical form to admit air upwardly therethrough and the top section 20 is of conical shape to support the lignite from falling through the sections 22. In Figs. 2 and 4

there is shown one means for connecting the sections of the grate together, the views 90 showing the intermediate sections only, although it will be understood that the base and top sections may be similarly connected with adjacent parts. In this structure each section 22 is provided with a desired number

95

of lugs or projections 23 at its upper edge adapted to lap beneath the adjacent upper section. Each lug 23 has a substantially radially extending slot 24 through which a bolt 25 is adapted to pass, the bolt being ad-

100

justable in the slot 24 for permitting the sections to be properly spaced apart. The bolt 25 is secured through the lower edge portion of the upper section and preferably has its head countersunk in the outer face

105

of the section. The bolt 25 forms a connection between the sections and admits the adjustment of the sections one upon the other to vary the air space between the sections.

The sections are held spaced apart by the 110 interpositioning of spacers about the bolt and between the sections. A bolt 25 and the

parts co-acting therewith are provided for each lug 23, and as many sections as desired may be built up to form a grate of the desired size to fit stoves of various sizes.

5 The top section 20 is of conical form and forms a cap for the grate structure to prevent the lignite from falling through the center of the device.

The improved grate structure is maintained in centered position by a holder 28. The holder 28 is in the form of a spider the arms of which are provided upon their outer ends with upwardly facing hooks or shoulders 29 directed inwardly and adapted to 15 engage the marginal edge portion of the lower section 22 to prevent lateral displacement thereof. The holder 28 is held in place on the grate 26 by adjustable blocks 30 slideable against the underside of the spider arms 20 and supported and clamped in position by bolts 31 which are slideable in radial slots 32 in the spider arms. The blocks 30 are adapted to project into the spaces between the bars of the usual grate 26 for holding 25 the spider and the improved grate rigidly in position.

In the use of this lignite grate, it may be placed in any stove or furnace of standard form, upon the ordinary grate of the ordinary stove or furnace as above set forth. The lignite grate may be adjusted in the number of sections and size of air spaces to accommodate the grate to the stove or furnace and obtain the best results therefrom.

35 The grate body supports the mass of fuel in the desired position in the firepot and insures the distribution of air centrally and evenly up through the grate and out into the mass.

40 An important feature of this invention is the adaptability of the grate to stoves and furnaces of various sizes without the necessity of providing specially constructed stoves and furnaces for the combustion of the lignite. Of course the sections may be made 45 circular as shown for cylindrical stoves and furnaces, or may be given any other desired

configuration for use with other shapes and constructions of the stoves and furnaces, the adjustability and adaptability still prevailing.

The mass of lignite while burning and slaking settles down over the inclined surfaces of the grate sections, and is supported on the grate 26, and the ashes may be sifted 55 through the latter by shaking in the usual manner.

The grate may, of course, be used with other fuel than lignite, but it is designed particularly for this use as prior structures 60 have prohibited the satisfactory handling of the lignite.

What is claimed is:

1. In combination with the ordinary stove grate, a supplemental grate composed of a 65 conical section and at least one frusto-conical section, means to hold the sections separated whereby air openings are provided therebetween, said means being adjustable to vary the area of said air openings, means 70 for adjustably securing the sections together, a base receiving said lowermost grate section, and adjustable blocks carried by said base and fitting in the openings of the ordinary grate.

2. In combination with the ordinary stove grate, a base fitted thereupon and having radial slots therein, blocks movable below and in the directions of said slots, means adjustable in said slots for supporting said 80 blocks, said blocks adapted to enter the openings in the ordinary grate, and a supplemental grate supported on said base.

3. In combination with the usual stove grate, a base supported thereon and consisting of a plurality of radial arms, said arms having shoulders near their free ends, a supplemental grate composed of hollow frusto-conical sections adjustably held together with air spaces therebetween and a top conical section, the lowermost section resting on said base and held in a central position by said shoulders.

ADALBERT A. RUMREICH.
